(57) **CLAIM**

The ornamental design for a crutch decoration, as shown and described.

DESCRIPTION

FIG. 1 is a perspective view of a crutch decoration showing my new design;

FIG. 2 is a top plan view thereof;

FIG. 3 is a bottom plan view thereof;

FIG. 4 is a side elevational view thereof;

FIG. 5 is an opposite side elevational view thereof; and, FIG. 6 is an end elevational view thereof, the opposite side of which is a mirror image.

Broken lines throughout the figures indicate related environment or unclaimed aspects of the invention and form no part of the claimed design.
